UNITED STATES PATENT OFFICE

THOMAS M. KIMES, OF MERRA, NEBRASKA

CLEAT FASTENING MEANS

Application filed June 18, 1932. Serial No. 618,069.

This invention relates to stapling means and more particularly to stapling means adapted for use in securing ribs or the like to a flexible member.

5 An object of this invention is to provide an exceedingly simple securing means for securing slats or ribs transversely of the length of a flexible belt such as is used in cultivating machines or the like, the securing means being such as to not only limit the possibility of splitting the slats or ribs but also to hold the canvas or belt relative to the slats or ribs so as not to tear the belt.

10 Another object of this invention is to provide a shield or hood which is adapted to engage about the surface of the rib, the shield or hood being engaged by a stapling means extending through the canvas or belt so that the rib can be easily secured to the belt.

15 A further object of this invention is to provide a device of this kind which is so constructed that it will not require the use of riveting tools or the like in the securing of the staple to the canvas or belt and about the rib.

20 The above and various other objects and advantages of this invention will in part be described and in part be understood from the following detailed description of the present 25 preferred embodiment, the same being illustrated in the accompanying drawing wherein:

Figure 1 is a fragmentary bottom plan view of a flexible belt with a cleat or rib disposed transversely thereof having a device constructed according to the preferred embodiment of this invention mounted thereon.

Figure 2 is a sectional view taken on the line 2-2 of Figure 1.

40 Figure 3 is a sectional view partly in detail taken on the line 3-3 of Figure 2.

Figure 4 is a sectional view taken on the line 4-4 of Figure 3.

45 Referring to the drawing wherein like characters of reference designate corresponding parts throughout the several views, the letter B indicates generally a belt or flexible member and the letter R indicates a rib extending transversely of the length of the canvas or belt B and which is adapted to be engaged by members carried by a farm imple-

ment such as a harvesting machine or the like for movement of the belt over the belt operating means.

In order to firmly and easily secure the belt B to the rib R, I have provided a staple, generally designated as 10, which comprises a relatively flat body plate 11 which is provided at each end thereof with tangs 12. A shield or U-shaped plate, generally designated as 14, is disposed about the rib R and has a configuration such as to closely engage about the surface of the slat or rib R beneath the belt B. This U-shaped shield or hood 14 is provided in the parallel legs thereof with slots 13, which slots are disposed intermediate the ends 60 of the parallel legs of the U-shaped member 14.

The material of the member 14 intermediate the slot 13 and the free end of each leg is outwardly offset, as at 15, so that the 70 tang 12 can be readily disposed intermediate the free leg 16 of the member 14 and the confronting face of the slat or rib R. The end of the tang 12 is adapted to project through the slot 13 and this tang 12 is preferably of a length slightly greater than the length of the parallel leg 16 so that the end of the tang 12 will project beyond the bight of the U-shaped member 14. In this manner, the projecting end portion of the tang 12 can 75 be turned over as at 17 so as to firmly clamp the shield or hood 14 about the slat or rib R and to hold the staple 10 against movement relative to the slat or rib R. In this manner, the canvas or belt B is firmly clamped on 80 one face of the slat or rib R and this clamping means not only engages about the slat or rib R so as to prevent splitting of this rib but the hood or shield 14 constitutes a means for engagement with the driving mechanism 85 for the canvas or belt B, so that the slat or rib R will not bodily contact with the driving means and thereby unduly wear this rib.

90 In the use of this cleat or rib fastening means, the staple 10 is initially formed with the tangs 12 straight. The cleat or rib 14 can then be disposed in the desired position transversely of the canvas or belt B and the staple then placed in a position where the tangs can be readily driven through the ma- 100

terial of the canvas or belt B in the desired position. The tangs 12 will be positioned one on each side of the slat or rib or cleat R and the shield or hood 14 can then be placed on the rib with the tangs 12 disposed in the offset portions 15 and projecting through the slots 13.

The projecting ends of the tangs 12 can then be bent over with any desired implement or tool and this bending action will tighten the body 11 of the staple against the canvas or belt B and firmly hold the slat or rib R against transverse movement relative to the canvas or belt B and due to the relatively wide body 11 of the staple, the staple will not unduly tear the material of the canvas or belt B.

This invention is an improvement over the construction disclosed in my copending application, Serial No. 568,184, filed October 10, 1931, for improvements in staples.

It is, of course, understood that various changes and modifications may be made in the details of construction and design of the above specifically described embodiment of this invention without departing from the spirit thereof, such changes and modifications being restricted only by the scope of the following claims.

30. What is claimed is:—

1. As a new article of manufacture, a staple having a tang at each end thereof and a U-shaped staple engaging member, said member having a portion of each leg offset outwardly and an aperture in each offset portion to receive the tangs, said tangs upon being bent reversely coacting with the staple engaging member to firmly secure a pair of articles between the staple and the 40 staple engaging member.

2. A means for fastening a cleat to a flexible belt comprising a staple including tangs at each end thereof adapted to project through the belt, a U-shaped cleat engaging member engaging about the cleat, said member having a portion of each leg offset outwardly and an aperture in each leg adjacent the junction of the leg with the bight of the member to receive the tangs of the staple, 50 said tangs when engaged in the apertures being bent reversely and outwardly whereby to clamp the cleat against one face of the flexible member.

In testimony whereof I hereunto affix my 55 signature.

THOMAS M. KIMES.
